United States Patent Office

Des. 182,333
Patented Mar. 18, 1958

182,333

BALUSTRADE UNIT

Sabato Della Gala, Worcester, Mass.

Application December 3, 1956, Serial No. 44,045

Term of patent 14 years

(Cl. D54—2)

FIG. 1

FIG. 2

FIG. 3

FIG. 4

Fig. 1 is a view in side elevation of a balustrade unit showing my new design;

Fig. 2 is a view in end elevation thereof; and

Figs. 3 and 4 are enlarged sections on the respective lines of Fig. 1.

I claim:

The ornamental design for a balustrade unit, as shown.
